UNITED STATES PATENT OFFICE.

FREDERICK S. CONKLIN, OF YONKERS, NEW YORK.

COMBINED TABLE.

1,309,509.

Specification of Letters Patent.

Patented July 8, 1919.

Application filed February 28, 1919. Serial No. 279,854.

To all whom it may concern:

Be it known that I, FREDERICK S. CONKLIN, a citizen of the United States, residing at Yonkers, in the county of Westchester and State of New York, have invented new and useful Improvements in Combined Tables, of which the following is a specification.

This invention relates to cabinets especially designed to be used for drying and ironing clothes and it consists in the novel features herein described and claimed.

An object of the invention is to provide a cabinet of the character indicated in which is mounted a number of pivoted racks which may be folded in the cabinet when not in use. An ironing board is pivotally mounted in the cabinet and is provided at one end with a heating apparatus. The said board may be folded into the cabinet when the device is not in use. Suitable props or legs are provided upon the board for holding the same in a horizontal position while in use.

In the accompanying drawings:

Figure 1 is a vertical sectional view of the cabinet.

Fig. 2 is a vertical sectional view of the same showing the parts in closed position and

Fig. 3 is a detail sectional view through the stove portion of the cabinet.

A head board 14 is mounted at the back wall of the body 1 and is provided at its opposite end portions with outstanding shelves 15 below which are slidably located drawers 16 adapted to be used for holding articles of any description. Spaced brackets 17 are mounted upon the head board 14 and a bumper 18 is mounted upon the said head board below and between the said brackets. A stove body 19 is pivotally mounted upon the brackets 17 and carries a gas burner 20. Open work plates 21 are positioned upon the body of the stove and may be located above the burner 20. The stove body 19 is provided at one side with a laterally disposed flue 22 having openings 23 located at the upper outer ends thereof. A board 24 is attached at one end to the body 19 in the vicinity of the flue 22 and braces 25 are interposed between the said board and the stove body 19. A gas service pipe 26 leads into the lower portion of the body 1 and is provided with a controlling valve 27. Pipe sections 28 are pivotally connected to

gether and one of the said pipe sections is 55 pivotally connected with the service pipe 26 and the other pipe section 28 is pivotally connected with the burner of the stove 19. The stove body 19 is provided at its rear side with a lug 29 which is adapted to encounter the bumper 18 when the stove body 19 is swung down to a horizontal position whereby the said stove body is held in a manner so that irons or other articles may be heated thereon. After the articles have 60 been heated and when one of them is in use it may be placed upon the upper end of the flue 22 above the openings 23 and thus the said articles may be maintained at a desired degree of temperature while it is being used 65 upon the board 24. Legs 30 are pivotally connected at one end with the stove body 19 and the said legs are provided with longitudinally disposed slots 31 having at their lower ends the laterally disposed extension 70 32. A prop member 33 is pivotally attached to the under side of the ironing board 24 and is provided with outstanding pins 34 adapted to move along the slots 31 and enter the extensions 32 thereof. 75

When the stove body 19 is swung down to a horizontal position the legs 30 may be swung down in contact with the floor whereby the pins 34 will move longitudinally of the slots 31 and the said pins will enter the 80 extensions 32 and hold the parts in proper position so that the board 24 may be used for ironing clothes. When the device is not in use the board 24 and the stove body 19 may be swung up toward the back of the 85 body 1 and the free end portion of the board 24 may be caught and secured under the hook 5 at the upper part of the back of the body 1. Also the legs 30 may be folded up against the under side of the 90 board 24 and the prop member 33 may be then swung down in close relation to the side of the board 24. In the body 1, near the top and adjacent the back thereof is a transverse cleat 4, and above the cleat is 95 a pivoted hook 5. The cleat supports the back member of a rack, the same including transverse rods 6 and horizontally disposed rods 7. The upper member of the rack is indicated, for distinction by the numeral 100 9 and carries transverse rods. To the member 9 is pivotally secured an extension 11 also provided with transverse rods. Pivot-

ally carried by the extension 11 is a supporting arm 12, the latter having the straight end bifurcated to be received in one of the transverse rods that connect the outer vertical members of the rack. These members are indicated by the numeral 10 and are pivotally connected to the upper member 9, so that the member 11 rests thereon when the rack is in operative position. When the rack is not in use the same is folded in the body 1 to the rear of the board 24 and the said board, being engaged by the hook 5 retains the rack in collapsed position in the body. When the elements are folded in the body the open face of the latter is closed by a suitable door disclosed in Fig. 2 of the drawings.

From the foregoing description taken in conjunction with the accompanying drawings it will be seen that a cabinet especially adapted to be used for drying and ironing clothes is provided and may be conveniently used in places where space is limited, and when the device is not in use the parts thereof may be folded together in compact relation and concealed behind the doors of the cabinet thus housing the parts and leaving the ornamental exterior surfaces of the doors and walls in view. While primarily devised as an ironing cabinet, it will be apparent from the foregoing description that the improvement may be used for general cooking purposes.

Having thus described the invention, what is claimed as new, is:—

In combination, a cabinet, a head board secured to the back wall thereof, spaced brackets mounted upon the head board, a rod extending at right angles between and at the bottom of said brackets and forming a bumper, a stove having lugs hingedly connected upon said bracket at its rear end, a lug carried by said stove at its bottom and rear end adapted to engage said bumper rod whereby to be held in a horizontal position and against rear movement, a service pipe extending practically through the bottom of the cabinet under said head board, a controlling valve connected to the upper end of said service pipe, a pipe pivotally coupled to the upper end of the said service pipe, a branch pipe pivotally coupled to said last named pipe at its outer end, a feed pipe projecting through the bottom of said stove to which is pivotally coupled said branch pipe, a longitudinal table board secured to said stove flush with its top surface and forming an extension thereof, a sectional support secured to said stove and board respectively and adapted to hold the latter in horizontal position with said stove, said support being foldable substantially in the same direction as the length of said board.

In testimony whereof I affix my signature.

FREDERICK S. CONKLIN.
